OIL BURNER SHIPPING PALLET

Ervin R. Wagner, Fort Wayne, Ind., assignor to Wayne Home Equipment Company, Fort Wayne, Ind.

Filed Mar. 10, 1960, Ser. No. 14,035

4 Claims. (Cl. 206—65)

This invention relates to a shipping pallet for gun-type oil burners in which the oil burners themselves cooperate with other packing elements to the end that more oil burners can be accommodated in a palletized container occupying the same volumetric space as previous palletized shipping containers containing fewer oil burners, thereby effecting substantial economies in shipping costs.

There has been a growing tendency in recent years to palletize articles of intermediate size for shipment, such as smaller motors and transformers; in a conventional palletized shipping container, the first row of articles is positioned upon a base member, a partition member is then placed upon the first row of articles and in turn supports a second row, and so on. While conventional palletizing techniques have been eminently satisfactory for articles having a generally symmetrical profile, such as motors and transformers, conventional gun-type oil burners present a difficult problem for palletizing by virtue of the fact that they comprise a housing portion which encloses the blower and generally has the driving motor, a transformer and fuel pump secured thereto, with an air tube extending outwardly from the housing portion a substantial distance. Thus, while gun-type oil burners have been successfully palletized in the past, the number of oil burners which could be accommodated in a single shipping carton of reasonable size was limited; this was because with the conventional palletizing technique of placing one layer of oil burners over another, the vertical height between layers was necessarily large in order to accommodate the air tubes of the oil burners in each layer.

It is accordingly an object of my invention to provide an improved shipping pallet construction for gun-type oil burners in which a substantially greater number of oil burners can be accommodated in a shipping carton of predetermined size than has previously been possible with prior oil burner palletizing arrangements known to the present applicant.

In accordance with the broader aspects of my invention, therefore, I provide an oil burner shipping pallet comprising a base member, a plurality of oil burners respectively having housing portions with air tubes extending therefrom and a partition member having a plurality of holes formed therethrough. A first group of the oil burners are disposed with their housing portions resting upon the base member and with their air tubes extending vertically upwardly and the partition member is supported by the housing portions of the first group of oil burners with the air tubes thereof respectively extending through the holes in the partition member. A second group of the oil burners is disposed with their housing members resting upon the partition member and with their air tubes extending vertically upwardly, the second group of oil burners being respectively displaced from the air tubes of the first group. Finally, cover means is provided covering the first and second groups of oil burners and the partition member and secured to the base member.

2

Further objects and advantages of my invention will become apparent by reference to the following description and the accompanying drawings, and the features of novelty which characterize my invention will be pointed out with particularity in the claims annexed to and forming a part of this specification.

In the drawings:

FIG. 1 is a view in perspective of my improved oil burner pallet showing the cover removed;

10 FIG. 2 is an exploded view showing the first steps in assembly of the pallet of FIG. 1;

FIG. 3 is an exploded view showing the next steps in assembly of the pallet of FIG. 1;

15 FIG. 4 is a plan view of one of the types of partition members employed in the pallet of FIG. 1;

FIG. 5 is a plan view of the other type of partition member employed in the pallet of FIG. 1;

20 FIG. 6 is a plan view showing one layer of oil burners in the pallet of FIG. 1; and

FIG. 7 is a fragmentary cross-sectional view showing the position of one oil burner in a pallet of my invention.

Referring now to the figures of the drawing, the gun-type oil burners which are accommodated in and form a part of the pallet of my invention are generally shown at 10 in FIG. 7. The oil burners 10 include a housing portion 12 which accommodates the blower and which has an air inlet portion 14 and fuel pump 16 at one end thereof and the motor 19 (FIG. 6) extending from the other end. An air tube 18 extends from the housing portion 12 as shown, and an annular mounting flange 20 is attached to the housing portion 12 and surrounds the air tube 18 at its inner end. An ignition transformer 22 is attached to the housing portion 12 and the particular gun-type oil burners for which my improved pallet was specifically designed have a flat portion 24 formed thereon with which the axis of the air tube 18 is generally perpendicular.

The improved pallet of my invention, generally identified at 30 in FIG. 1 comprises a base member 32 formed of suitable material, such as the corrugated paper board commonly used for packing material; base member 32 is generally rectangular in configuration and has an upwardly extending peripheral flange 34 formed therearound. Spaced parallel wooden skids 36 may be secured to the bottom surface of base member 32 in accordance with conventional practice.

In accordance with my invention, I employ two different forms of partition members or dividers as shown in 50 FIGS. 4 and 5 and respectively identified as "A" and "B." Partitions "A" and "B" are each formed of suitable material such as corrugated board, and both are rectangular in form, as shown; partitions "A" and "B" are the same size and are slightly smaller than base member 32 in order to be accommodated within peripheral flange 34, as will be hereinafter described.

The pallet 30 shown in the drawings is designed to accommodate six oil burners in each layer, and thus, partitions "A" as shown in FIG. 4 have six round holes 38 cut therethrough disposed in two spaced parallel rows, as shown by dashed lines 40 and 42, the holes 38 in each row being equally spaced as shown. Inspection of FIG. 4 will reveal that the holes 38 define a rectangle 44 with its longitudinal and transverse center lines 46 and 48 being respectively displaced from the longitudinal and

transverse center lines 50 and 52 of the partition member "A." As will be hereinafter more fully described, round holes 38 in partition members "A" are proportioned snugly to accommodate air tubes 18 of the oil burners 10.

The partition members "B" also have six holes 54 cut therethrough respectively in alignment with the six holes 38 in the partition members "A." Partition members "B" also have six rectangular holes 56 cut therethrough. Rectangular holes 56 are respectively associated with but spaced from round holes 54, and, as it will be observed in FIG. 5, rectangular holes 56 are disposed at an angle with respect to the sides of partitions "B."

Referring now particularly to FIG. 2, in assembling the pallet 30 of my invention, a first partition "B," identified as B-1 is positioned on base member 32 within the flange portion 34. A first group 58 of six oil burners 10 are then positioned with the flat portions 24 of their housing 12 respectively seated in the rectangular openings 56 of partition B-1 and thus resting on base member 32. Since the rectangular holes 56 are respectively disposed at an angle to the sides of the partition B-1, it will be observed that the oil burners 10 are also angularly disposed so that the motor 19 of one oil burner of one row is positioned beside the air opening portion and oil pump of the adjacent burner of the same row. As best seen in FIG. 7, the air tubes 18 of the first group 58 of oil burners thus extend vertically upwardly. In order to provide additional support for the next partition member A-1, a pair of rectangular elements 60 and 62 formed of suitable material such as corrugated board are then positioned on base member 32 within the flange 34 respectively surrounding the two rows of oil burners 58; rectangular elements 60 and 62 have a height substantially the same as the height of flanges 20 of oil burners 58 above the first partition member B-1.

Referring now particularly to FIG. 3, a first partition member A-1 is now positioned resting upon the upper edges of the rectangular elements 60 and 62 and with the air tubes 18 of the first group of oil burners 58 respectively extending through holes 38 so that the partition member A-1 also rests upon the mounting flanges 20. It will here be observed that the first partition member A-1 has been rotated in its own plane by 180° with respect to the first partition B-1 so that the circular holes 38 accommodate the air tubes 18 of the first group of burners 58. A second partition member B-2 is now positioned resting upon the first partition member A-1 with its circular holes 54 respectively in alignment with the holes 36 of the partition member A-1 and with the air tubes 18 of the first group of oil burners 58 extending therethrough. It will be observed that the partition member B-2 is likewise rotated in its own plane by 180° from the first partition member B-1.

A second group of six oil burners 64 are then positioned with the flat portions 24 of their housing portions 12 respectively seated in the rectangular holes 56 of partition member B-2 and thus resting on partition A-1, and with their air tubes 18 thus extending vertically upwardly. As in the case of the first row of oil burners 58, the second row 64 by virtue of the angular alignment of the rectangular holes 56 in the partition member B-2 are angularly disposed, with the motor 19 of one burner being adjacent the air inlet portion 14 and oil pump 16 of the adjacent burner. Furthermore, it will be observed, with particular reference to FIG. 6, that the second group of oil burners 64 are displaced from the blast tubes 18 of the first group of burners which project through the partition member B-2 upon which the second group of oil burners 64 rests; the blast tubes 18 of the first group of oil burners 58 extend respectively upwardly in the spaces between the burners of the second group 64. In order to provide additional support for the next partition members A-2 and B-3 and the oil burners thereon, tubular elements 66 formed of any suitable material such as corrugated board are positioned over the blast tubes 18

of the first group of burners 58, tubular members 66 having substantially the same height as the vertical height between partition member B-2 and the flanges 20 of the second group of oil burners 64.

5 Another partition member "A," identified as A-2, is then positioned so that it rests upon the upper edges of tubular element 66 with blast tubes 18 of the second group of burners 64 respectively extending upwardly through its circular holes 38 so that the partition member A-2 also rests upon the flanges 20. It will now be observed that partition member A-2 has been rotated in its own plane 10 180° with respect to partition member A-1 and that its circular holes 38 are in vertical alignment with the unused circular holes 54 in the bottommost partition member B-1. A third partition member B-3 is then positioned 15 on the partition member A-2 with its circular holes 54 respectively in alignment with circular holes 38 of partition member A-2. Thus, it is seen that the partition member B-3 has been rotated in its own plane by 180° from the partition member B-2 and is in alignment with the bottommost partition member B-1. A third group of oil burners 68 is then positioned with their flat portions 24 20 of their housing portions 12 respectively seated in the rectangular holes 56 of partition member B-3, thus resting upon the underlying partition member A-2.

Assembly of the pallet is then continued as hereinbefore described with partition members A-3 and B-4 resting upon the oil burners of group 68, group 70 of oil burners resting upon partition members A-3 and B-4, 30 partition members A-4 and B-5 resting upon group 70 of oil burners and group 72 of oil burners resting in turn upon partition members A-4 and B-5. It will be observed that in accordance with my invention, each cooperating pair of partition members A and B are rotated or reversed by 180° in their own plane from the adjacent pair of partition members A and B above and below it, thereby providing for the "nesting" of the oil burners of one layer or group and the blast tubes of the next lower group, as seen in FIG. 6.

40 In order to complete the pallet, a single partition member A-5 is positioned resting upon the next lower tubular elements 66 and the flanges 20 of the oil burners of the uppermost group 72. The air tubes 18 of the oil burner group 72 which project upwardly through circular holes 38 in the partition member A-5 are again surrounded by tubular elements 66. Tubular cover member 74 is then positioned over the oil burners and partition members with its lower extremity being seated within peripheral flange 34 of base member 32. The pallet is then held 45 in assembled relation by conventional metal bands 76 which surround the cover member 74 and the base member 32.

50 In an actual oil burner pallet constructed in accordance with this invention, base member 32 was formed of 275 pound test corrugated board and was 52 $\frac{3}{4}$ inches long by 50 $\frac{1}{2}$ inches wide, with flange 34 being 3 inches high. Rectangular elements 60 and 62 were formed of 275 pound test corrugated board and were 8 $\frac{1}{2}$ inches high, partition members A and B were formed of 275 pound test corrugated board and were 43 $\frac{3}{8}$ inches long by 41 $\frac{1}{4}$ inches wide. Tubular elements 66 were formed of 275 pound test corrugated board and were 7 $\frac{3}{4}$ inches long and 4 $\frac{1}{8}$ inches square (inside). Cover member 74 was 55 formed of 350 pound test corrugated board with its top 78 being 44 inches long and 41 $\frac{1}{8}$ inches wide, and cover member 74 being 49 inches high. With this arrangement, thirty (30) oil burners are accommodated in five (5) layers or groups of six (6) burners, as shown in FIG. 6 in a completely palletized carton 46 inches long by 43 inches wide by 49 inches high, having a volume of 56.08 cubic feet. By contrast, the oil burner pallet previously employed by applicant's assignee for the same model of oil burner accommodated only eighteen (18) oil burners in a pallet 43 inches long by 38 inches wide by 50 inches high, with a total volume of 47.28 cubic feet. It is thus 60 readily seen that with my improved oil burner shipping

pallet, twelve additional burners can be shipped in a pallet occupying only slightly greater volumetric space as the previously employed pallet, thus obviously effecting very substantial savings in shipping costs.

While I have illustrated and described a specific embodiment of my invention, further modifications and improvements will occur to those skilled in the art, and I desire therefore in the appended claims to cover all modifications which do not depart from the spirit and scope of my invention.

What is claimed is:

1. An oil burner shipping pallet comprising: a rectangular base member; a plurality of oil burners respectively having housing portions with air tubes extending therefrom; a plurality of first rectangular partition members each generally coextensive with said base member and having a plurality of holes formed therethrough in at least two spaced-apart rows respectively having at least two equally spaced holes therein, the holes of each said partition member defining a rectangle with its transverse and longitudinal center lines respectively displaced from the transverse and longitudinal center lines of said partition member; a plurality of second rectangular partition members each generally coextensive with said first partition members and having a plurality of first holes formed therethrough respectively in alignment with the holes of said first partition members, each of said second partition members having a plurality of second holes formed therethrough respectively equally spaced from said first holes; one of said second partition members resting upon said base member and in alignment therewith; a first group of said plurality of oil burners having their housing portions respectively seated in said second holes of said one second partition member with their air tubes respectively extending vertically upwardly; one of said first partition members resting upon the housing portions of said first group of oil burners with the air tubes thereof respectively extending through the holes of said one first partition member, said one first partition member being rotated by 180° in its own plane with respect to said one second partition member and being in vertical alignment therewith; a second of said second partition members resting upon said one of said first partition members, said second of said second partition members being rotated by 180° in its own plane with respect to the first of said second partition members and having its first holes respectively in alignment with the holes of said one first partition member and with the air tubes of said first group of oil burners respectively extending therethrough; a second group of said plurality of oil burners having their housing portions respectively seated in said second holes of said second partition members and with their air tubes respectively extending vertically upwardly; a second of said first partition members resting upon the housing portions of said second group of oil burners with the air tubes thereof respectively extending through the holes of said second of said first partition members, said sec-

ond of said first partition members being rotated by 180° in its own plane with respect to the first of said partition members and having its holes respectively in alignment with the first holes of the first of said second partition members; a third of said second partition members resting upon said second of said first partition members, said third of said second partition members being rotated by 180° in its own plane with respect to the second of said second partition members and having its holes in alignment with the respective holes of the first of said second partition members and with the air tubes of the second group of oil burners respectively extending through its first holes; a third group of said plurality of oil burners having their housing portions respectively seated in the second holes of said third of said second partition members with their air tubes extending vertically upwardly; and a tubular cover member enclosing said oil burners and said partition members and secured to said base member.

2. The combination of claim 1 wherein said second holes of said second partition members are generally rectangular and are disposed at an angle to the sides of said second partition member, and wherein each of said oil burner housing portions has a flat portion former thereon with the axis of said air tube being generally perpendicular thereto, said flat portions being respectively seated in said second openings in said second partition members.

3. The combination of claim 1 wherein said base member has an upwardly extending peripheral flange portion formed thereon, wherein said first of said second partition members is disposed within said flange portion; and further comprising a plurality of rectangular elements extending between said first of said second partition members and the first of said first partition members for supporting the same and the oil burners thereon, said rectangular elements respectively surrounding the oil burners in each row of said first group; and a plurality of tubular elements respectively surrounding said air tubes, the tubular elements surrounding the air tubes of said first group of oil burners respectively extending between the second of said second partition members and the second of said first partition members for supporting the same and the oil burners thereon.

4. The combination of claim 1 wherein the housing portion of each of said oil burners has an annular mounting flange surrounding the inner end of the air tube, and wherein the first and second ones of said first partition members respectively rest upon said flanges of the first and second groups of oil burners.
